UNITED STATES PATENT OFFICE.

WILLARD LE GRAND BUNDY, OF BINGHAMTON, NEW YORK.

CLOCK MECHANISM FOR TIME-RECORDERS.

No. 831,498.

Specification of Letters Patent.

Patented Sept. 18, 1906.

Application filed March 18, 1901. Serial No. 51,573.

To all whom it may concern:

Be it known that I, WILLARD LE GRAND BUNDY, a citizen of the United States, and a resident of Binghamton, in the county of 5 Broome and State of New York, have invented certain new and useful Improvements in Clock Mechanism for Time - Recorders, of which the following is a specification.

My invention relates to clocks, particularly to clocks used in workmen's time-recorders.

It has for its object to simplify the construction of the mechanism for bringing the workman's time-card on the printing-line in 15 workmen's time-recorders, known as "card-machines," to make said time-recorders easy of operation and to lessen the chances of any mistakes being made upon the workman's time-card in the printing of his arrival and 20 departure.

It has also for its object to simplify the construction of clocks known as "calendar-clocks."

I have shown my improvement in the form 25 preferred for use in workmen's time-recorders, known as "card-machines," although in many of its features the invention could be used in various other machines.

In the drawings I have shown the preferred 30 form and will now proceed to describe the same as embodied in a clock for use in card-machines.

Referring to the drawings, which show the preferred form of my improvement as embodied in clocks for use in card-machines, similar figures represent similar parts.

Figure 1 is a front view showing a dial and a portion of the mechanism for raising or lowering a card-holder. Fig. 2 is a front view of 40 my improved clock with the dial removed, showing a portion of a disk with the days of the week imprinted thereon and mechanism for rotating the same. Fig. 3 is a top view of my improved clock mechanism looking downward from the top. Fig. 4 is a view of my improved clock mechanism with the dial and front plate removed.

In the drawings, 1 is a clock-dial with a portion 2 cut away, so as to permit the day of 45 the week, which is on the dial 17, to be seen through it.

3 is a workman's time-card which is carried in the card-holder 41, supported on the supports 42 42, and which is raised and low-

ered by my improved mechanism, hereinafter 55 described.

Referring to Fig. 2, 4 is an eccentric cam fixedly secured to the shaft, upon which is carried the hour - hand clock, so that the cam will make one complete revolution every 60 twelve hours or as often as the hour-hand makes a complete revolution of the clock-dial. 5 is an arm fixedly mounted upon the rock-shaft 6, which also carries a double arm 7. The rock-shaft 6 is loosely mounted in 65 the plates 8 9, in which the entire clock-works are mounted. This shaft 6, carrying the arms 5 and 7, is so loosely mounted in the shaft that the arms 5 and 7 will by gravity always seek the lowest position. 43 and 44 70 are the gear-wheels supported on the shaft, to which is attached the mainsprings operating the clock. 10 is a supplemental spring which rotates shaft 11, on which is fixedly mounted gear-wheel 12, which rotates fly-wheel 13 75 through a chain of gearing 14, 15, and 16. As shown in Fig. 4 in the drawings, the spring 10 is not permitted, except at a predetermined time, to exercise its operation, by reason of the locking device, which is as follows: 80 Arm 18 is loosely pivoted to plate 8 at 18^a, so that by gravity it will seek its lowest position. Arm 18 has a portion 19 and 22 bent over at its extreme off end and near its center, so as to engage in a dent on the plate 85 20, fixedly secured to the shaft 21, and a cut-out 23 on the plate 24, fixedly secured to the shaft 25, by means of which the chain of gearing operating the governor-wheel 13 is prevented from operating except when released by means hereinafter described. 17 90 is a dial fixedly mounted on the shaft 26, upon which dial is printed the days of the week in duplicate with the letters "A. M." and "P. M." to designate fore and after noon. 95 Upon the shaft 26 is also fixedly mounted the eccentric plate 27 and the toothed gear 28, by means of which the dial is rotated or locked in position through the operation of spring-pressed pawl 29. Mounted upon the outer end of shaft 25, which carries gear 14 100 and which extends through plate 9, in which the entire mechanism is inclosed, is fixedly secured gear 30, which engages with and rotates gear-wheel 31, on which are mounted two studs 31^a 31^a, which engage with and rotate toothed gear 28, fixedly secured to the shaft 26, which also rotates the eccentric

plate 27 and the dial 17. The teeth on the gear-wheels 30 and 31 are in the ratio of one to two, so that upon every complete revolution of the gear 30 the gear 31 is revolved one-half and through means of the studs the gear 28 is rotated one tooth. Mounted on plate 9 is a shaft 32, upon which is loosely mounted, so as to fall by gravity, the arm 33, which arm carries at its outer end the stud 33^a, which rests upon the eccentric plate 27 and which is raised or permitted to seek its lowest position, according to the position in which this eccentric plate 27 remains. The arm 33 carries about midway a rod 34, which is connected at its lower end to an arm 35, one end of which is loosely mounted in plate 9 at 36. This arm 35 also has supported on it arm 37, the lower end of which is pivoted near the center of arm 38, one end of which is pivoted in the frame or box in which the clock is inclosed, the other end of which supports, through the link 40, the card-rack. The mode of operation of my improved clock is as follows: Every twelve hours or at 25 twelve o'clock the plate 4 reaches a position which raises the arm 5 and rocks rock-shaft 6, raising arm 7, which arm strikes against lug 18^b on gravity-arm 18 and raises gravity-arm 18 so as to unlock the portions 22 and 19 30 from the plates 24 and 20, respectively. The supplemental clock-spring 10 then begins to operate and rotates the chain of gearing 14, 15, and 16 and the governor gear-wheel 13. At the same time the gear 30 on the extreme 35 end of the shaft 25 is rotated one revolution, thereby revolving the gear 31, upon which is mounted the stud 31^a, one stud of which engages with the toothed gear-wheel 28 and revolves it one tooth. The toothed gear-wheel 40 28 being fixedly secured to the shaft 26 when it is revolved, it also revolves the dial-plate 17 one point, so as to bring the next day or the next half-day into view through the cut-out 2 on the clock-face 1. At the same time 45 that the dial carrying the days printed thereon is revolved the eccentric plate 27 is revolved and the stud 33^a of the arm 33, resting upon the outer periphery of the eccentric plate 27, is raised, thereby raising the card-rack one point through the raising of the rods 34, 35, 37, and 38, so as to bring the portion 50 of the card marked "A. M." or "P. M." on the printed line A A, as shown in Fig. 1 of the drawings. The printing-line on the card is 55 at "Sunday P. M." as is also shown by a cut-out 2 on the clock-face 1. Immediately after twelve o'clock the cam-plate 4 permits arm 5 to drop to its lowest position, and at the same time the gears 14, 15, and 16 are locked and 60 the supplemental spring is restrained from operating. The eccentric plate 27 is so arranged that between "Sunday P. M." and "Monday A. M." the stud 33^a will be raised to its farthest position from the shaft 26 upon 65 which the eccentric plate 27 is carried, and

immediately after having been raised to its farthest position it will be permitted to drop by gravity to its lowest position or to its position nearest to the shaft 26, upon which the eccentric plate is carried, which at the same 70 time permits the card-rack to drop to "Monday A. M."

By the above-described means the operator is permitted by looking at the clock-face to ascertain if the period of time which will be 75 imprinted on his card is correct before he operates the recorder.

Many modifications and changes could be made without departing from the spirit of my invention.

What I claim as new, and desire to secure by Letters Patent, is—

1. In a time-recorder, a clock and means for operating same, the face of said clock having an opening therein through which periods of time can be seen, a supplemental clock-movement having a dial with periods of time imprinted thereon, a supplemental spring and gears for actuating said dial, an eccentric cam integrally mounted on the shaft 85 carrying the said dial and a rocking shaft, one end of which is mounted in the framework of the clock mechanism and the other end having a pin resting on the outer edge of the said eccentric cam, said rocking shaft having attached to it a series of rods for raising and lowering a card-rack, an eccentric cam fixedly mounted on a shaft carrying the hour-hand of said clock and an arm one end of which rests on the outer surface of the said 95 cam, the other end being fixedly mounted on a shaft carrying an arm adapted to lock and unlock the said supplemental spring and gears, whereby the said dial carrying the periods of time may be rotated a predetermined distance. 100

2. In a time-recorder, a clock and means for operating same, the clock-face having an opening therein through which periods of time can be seen, a supplemental clock-movement having a dial with periods of time imprinted thereon so arranged that only one 110 of the said periods of time will register with the openings in the clock-face at a time, a supplemental spring and gears for actuating 115 said dial, a card-rack for carrying a record-card, an eccentric cam fixedly mounted on the shaft carrying said dial and a rocking shaft, one end of which is mounted in the framework of the clock mechanism and the 120 other end having a pin resting on the outer edge of the said eccentric cam, said rocking shaft having a series of rods connected with it for raising and lowering the card-rack so as to bring the same period of time on the card 125 in the card-rack upon the printed line as is shown in the opening on the face of the clock and means for holding same in that position a predetermined length of time, an eccentric cam fixedly mounted on the shaft 130

carrying the hour-hand of the clock, an arm one end of which rests on the outer surface of the said cam, the other end of same being fixedly secured to a rocking shaft carrying 5 another arm for locking and unlocking the supplemental mechanism for operating the dial.

In testimony whereof I have signed my name to this specification in the presence of two subscribing witnesses.

WILLARD LE GRAND BUNDY.
